UNITED STATES PATENT OFFICE.

PETER SORENSEN, OF WOLBACH, NEBRASKA.

HEN'S NEST.

1,245,053.

Specification of Letters Patent.

Patented Oct. 30, 1917.

Application filed February 21, 1917. Serial No. 150,106.

To all whom it may concern:

Be it known that I, PETER SORENSEN, a citizen of the United States, residing at Wolbach, in the county of Greeley and State of Nebraska, have invented new and useful Improvements in Hens' Nests, of which the following is a specification.

The present invention contemplates the provision of a hen's nest, more particularly 10 of the collapsible type.

The primary object of the invention resides in the provision of a device of the above-stated character which is novel in construction, efficient in use, and one where- 15 by the parts constituting the device may be readily disconnected and thoroughly cleansed in order to maintain the nest in a clean and sanitary condition at all times.

A still further object of the invention is 20 the production of a device of the above-stated character which may be manufactured at a minimum cost, well adapted for the purposes intended, and which may be readily collapsed in a compact form, thus occupying but a minimum amount of space during the storage or transportation of the 25 same.

With the above and other objects in view, the invention consists in the novel features, 30 details of construction and combination of parts which will hereinafter be more fully set forth, illustrated in the accompanying drawings and pointed out in the appended claims.

35 In the drawings:—

Figure 1 is a perspective view of a nest constructed in accordance with my invention.

Fig. 2 is a view similar to Fig. 1 showing 40 the nest in open position.

Fig. 3 is a longitudinal sectional view.

Fig. 4 is a detail perspective view of the partition walls removed from the housing.

Fig. 5 is a detail sectional view clearly 45 illustrating the manner of connection of the ridge bar with the partition wall and also illustrating the manner of connecting the top sections thereto.

Reference being had more particularly to 50 the accompanying drawings, 5 denotes a portable hen's nest preferably constructed of sheet metal or like material, and of collapsible type, embodying a bottom wall 6, opposite end walls 7, and opposite side walls 8. 55 The bottom wall 6, is provided along its opposite transverse edges with upturned

sockets 9 in which is slidably mounted depending bulged extensions 10, formed on the bottom transverse edge of the opposite end walls 7, thus detachably connecting the 60 latter with the bottom 6, while the opposite longitudinal edges of the bottom wall 6 of the nest are likewise provided with upturned sockets 11, in which is slidably mounted the curved extension 12 formed on 65 the bottom longitudinal edge of the opposite side walls 8, thus serving to detachably and hingedly connect with the bottom wall 6, the side walls 8 of the nest.

It will of course be understood that the 70 manner of connecting the side walls 7 with the bottom will permit hingedly mounting these walls on the bottom if so desired. Extending longitudinally upon the bottom wall 6, is a longitudinally extending partition 75 wall 13 which exceeds the height of the end walls 7, thus positioning the uppermost longitudinal edge of the partition wall at a point above the upper edge of the end walls. The object in so constructing this partition 80 wall will be more fully explained as the description of the invention is proceeded with. Formed upon the extended longitudinal edge of the partition wall 13, and formed from the material of which the partition 85 wall is constructed, is a plurality of locking tongues 14, while similar tongues 15 are provided on the opposite vertical edges of said partition wall, said tongues 15, as well as the tongues 14, being arranged in pairs. The 90 purpose of the locking tongues 14 is to connect and mount the ridge bar 16, upon the uppermost longitudinal edge of the partition wall 13, whereas the locking tongues 15, protrude through the vertically alined slots 85 17 formed in the opposite end walls 7, thus serving to connect the latter with said partition wall. The locking tongues 14 by being arranged in spaced pairs, are adapted when the same are extended through the slots 18, 100 formed in the broadened portion 19 of said ridge bar, to be bent in opposite directions, thus establishing permanent connection of the ridge bar with said partition wall. Likewise, the tongues 15, which are disposed 105 in spaced pairs after being inserted through the alined slots 17 of the end walls are bent in opposite directions. This arrangement of the respective locking tongues 14 and 15, establishes a detachable connection of the 110 partition wall with the respective end walls and ridge bar, affording convenient means

for ready assembling or disassembling the partition walls with respect to the nest should occasion so demand that the nest be cleansed, stored or transported.

5 The opposite longitudinal edges of the material forming the ridge bar 16 are curved in a downward and inward direction providing throughout the length of the ridge bar, spaced bearings 20, in which are journaled curved trunnions 21 formed on the innermost longitudinal edges of each of the closures 22 forming the top of the nest. By 10 this form of construction the top sections 22 are hingedly connected with the ridge bar 16 for vertical swinging movement. Each 15 of the closures 22 is provided along its opposite transverse edges with downturned flanges 23, having an aperture 24 in which are inserted the hooked ends 25 of the coiled springs 20. The coil springs 26 are adapted to clear 20 the end walls when the top sections 22 are swung in a closed or downward position and when said sections are in such position, these springs will contract and retain both in a 25 closed position against any accidental outward swinging movement. Whereas, when it is desired to swing the sections 22 of the nest to an open position and the sections 30 are swung to a distance above the plane of the ridge bar, the tension of the springs 26 will automatically draw the sections 22 toward one another and thus tend to automatically elevate the top sections 22 and retain 35 said sections in such elevated or raised position.

The partition wall 13 throughout its entire length and at spaced intervals apart is stamped out to provide pairs of superposed openings 27, through which the tongues 28 40 formed on the inner vertical edge of the transverse partition walls 29, protrude, and by the bending of these tongues upon the longitudinal partition wall 13, will establish a detachable connection of the former with 45 the latter.

From the foregoing taken in connection with the accompanying drawings, the nature and advantages of the invention will be readily apparent, although I desire to have 50 it understood that I do not limit myself to the precise construction and arrangement herein illustrated and described, and that various changes may be resorted to when desired as fall within the scope of the appended claims.

I claim:—

1. A hen's nest comprising a bottom wall and end walls detachably connected with the bottom wall, a partition wall having connection with the end walls and having a portion extending above said end walls, a member detachably connected with the extended

portion of said partition wall, and a plurality of closures hingedly connected with said member, and yieldable means connecting the 65 closures together.

2. A hen's nest comprising a bottom wall and end walls detachably connected with the bottom wall, a partition wall having connection with the end walls and having a portion 70 extending above said end walls, a member detachably connected with the extended portion of said partition wall, and a plurality of closures hingedly connected with said member, and yieldable means connecting the 75 closures together, said means tending to retain the closures in both closed and open positions.

3. A nest of the character described embodying a partition wall, a member reposed 80 upon the upper edge of the partition wall and having detachable connection therewith, said member having its opposite edges bent to provide spaced bearings, a pair of flanged closures, each of said closures having its confronting longitudinal edge bent to provide the same with trunnions, the trunnions of said sections being arranged in the bearings of said member for hingedly connecting the sections thereto, and yieldable means 85 detachably connected at one end with the flange of one closure and at its opposite end with the flange of the opposite closure for retaining said closures in either a raised or lowered position.

4. A hen's nest embodying end walls, a partition wall connecting the end walls together, closures hingedly connected with said partition wall and a single member terminally connected with the ends of each closure 100 for operatively holding the closures in either an open or closed position.

5. A hen's nest including end walls, a partition wall connecting the end walls together, a pair of closures hingedly connected 105 with the partition wall, and means terminally connected at one end with one end of one of said closures and connected at its opposite end with one end of the opposite closure for connecting the closures together, 110 said means tending to exert an inward pull on the closures for automatically retaining the same in either a closed or open position.

6. A hen's nest comprising end walls, a pair of closures, and yieldable means connected at one end with one closure and at its opposite end with the other of said closures for operatively connecting the closures together, said yieldable means being disposed in spaced relation with the end walls of the 120 nest.

In testimony whereof I affix my signature.

PETER SORENSEN.
